UNITED STATES PATENT OFFICE.

PHERREL DRAPER, OF BINGHAM CANYON, UTAH, ASSIGNOR OF FORTY-NINE ONE-HUNDREDTHS TO OTTO LEE, OF BINGHAM CANYON, UTAH.

WASHING-MACHINE.

1,184,684.

Specification of Letters Patent. Patented May 23, 1916.

Application filed January 14, 1915. Serial No. 2,252.

To all whom it may concern:

Be it known that I, PHERREL DRAPER, a citizen of the United States, residing at Bingham Canyon, in the county of Salt Lake and State of Utah, have invented certain new and useful Improvements in Washing-Machines, of which the following is a specification.

My invention relates to improvements in washing machines, and an object of my invention is the provision of a machine which will thoroughly and quickly cleanse the clothes without contact, thus insuring the highest degree of efficiency without injury to the clothes.

Another object of my invention is the provision of a machine which can be operated by hand or power and which will quickly and thoroughly cleanse the articles without injury thereto.

Another object of my invention is the production of a washing machine which will possess merit in point of simplicity, durability and inexpensiveness, and which will be practical from every point of view.

To attain the desired objects my invention consists of a washing machine embodying novel features of construction and combination of parts substantially as shown, described and claimed herein.

In order that the detailed construction and operation of my invention may be understood and its advantages fully appreciated, I have shown in the accompanying drawings a washing machine constructed in accordance with my invention.

Figure 1 represents a vertical central sectional view of a washing machine embodying my invention, and Fig. 2 represents a side elevation of the machine.

Referring by letter to the drawings: the letter A, designates the outer receptacle or vessel of the desired size supported on legs B, and having the pair of lateral guiding ears C, and the pair of depending brackets D, in which bears the shaft E, having end crank arms F, and central crank yoke G. To the said yoke G is connected the inner end H, of the pitman H', whose outer end H'', is connected the lower end of the hand lever J, fulcrumed at J', to the lateral arm K, which arm is secured rigidly to the bottom of the vessel. Also upon the shaft E, is mounted a wheel L, operated by a belt L', from a suitable driving source. From this

construction it will be noted that the shaft E, is revolved either by hand through the medium of the hand lever, or by power applied through the belt and wheel and to the crank arms F, is secured the lower ends M, of the bail M', to whose central portion M², is connected at N, the upper end of the piston rod N', carrying the piston head N².

The rotation of the shaft E, reciprocates the bail M' which is guided in the lateral ears C and reciprocates the piston rod N' with its head N², and the said head moves in the vertical cylinder O, rising centrally from the clothes receptacle P. The receptacle has an opening P' in its bottom wall leading from the cylinder, is supported in the vessel upon suitable feet Q, is provided with perforations R, in its bottom and side walls and is supported upon the vessel by the flanged rim S, which also forms a closure between the walls of the outer vessel and clothes receptacle.

In operation a proper amount of water is placed in the vessel and clothes receptacle and in this condition the soiled garments are placed in the receptacle and the reciprocation of the piston head, in the manner stated, forces air and water rapidly through the clothes and imparts the desired agitation to absolutely remove all soil and effect a rapid and thorough cleaning without damage to the articles.

The machine can be operated by hand or power, will quickly cleanse any kind of fabric without injury and generally speaking is efficient, desirable and practical.

While the machine is particularly adapted for washing clothes it will be understood that it may be used for washing dishes; also that the machine may be made of any size or shape and of either wood or metal; also is thoroughly sanitary as every part can be removed and cleaned; and the machine may be operated from above or below and will prove useful either in the household or laundry.

I claim:

A washing machine, consisting of a supported receptacle, a pair of brackets depending from said receptacle, a pair of lugs extending laterally from the receptacle, a shaft having a central cranked portion and cranked ends mounted in said brackets, operating means connected with the central cranked portion of said shaft, a yoke guided

in the lateral lugs and having its lower ends connected to the cranked ends of said shaft, a clothes container mounted in said receptacle and comprising a perforated vessel having a flanged rim fitting on the top of said receptacle, a pump cylinder therein and a piston in said cylinder connected with and operated by the yoke said cylinder having a free opening in its bottom and adapted

to force the water from the cylinder into 10 the outer receptacle and through perforations in said receptacle onto the clothes.

In testimony whereof I affix my signature in presence of two witnesses.

PHERREL DRAPER.
